(57) **CLAIM**

The ornamental design for a straw tip as shown and described.

DESCRIPTION

FIG. 1 is a front view of the straw tip shown in a use configuration with environment showing my new design; the back view of the straw tip is a mirror image of the front view;

FIG. 2 is a top view of the straw tip;

FIG. 3 is a bottom view of the straw tip;

FIG. 4 is a right side view of the straw tip, and the left side view is a mirror image of the right side view; and,

FIG. 5 is a perspective view of the straw tip.

The dash-dash broken lines in FIG. 1 depict the environment of a conventional straw that forms no part of the claimed design.

The dash-dot-dash broken lines in FIG. 1, FIG. 2, FIG. 3, FIG. 4 and FIG. 5 form no part of the claimed design.

The dash-dot-dot broken lines in FIG. 2, FIG. 3, and FIG. 5 is a broken line boundary showing the circular features of the design.
